UNITED STATES PATENT OFFICE.

JACOB ZITZERMAN, OF BROOKLYN, NEW YORK.

DESIGN FOR A CONSOLE CABINET OR SIMILAR ARTICLE.

Application filed April 8, 1925. Serial No. 13,070. Term of patent 14 years.

To all whom it may concern:

Be it known that I, JACOB ZITZERMAN, a citizen of Russia, and resident of the city of New York, borough of Brooklyn, in the county of Kings and State of New York, have invented a new, original, and ornamental Design for a Console Cabinet or Similar Article, of which the following is a specification.

Reference is had to the accompanying drawing in which the figure is a perspective view of a console cabinet or similar article embodying the design.

I claim:

The ornamental design for a console cabinet or similar article, as shown.

JACOB ZITZERMAN.
